FOREIGN PATENT DOCUMENTS

DE 10247163 11/2015

Primary Examiner — Jonathan J Han(74) *Attorney, Agent, or Firm* — Marshall A. Lerner; Steven J. Kim; KLEINBERGER & LERNER, LLP(57) **CLAIM**

The ornamental design for a shoe upper component as shown and described.

DESCRIPTION

FIG. 1 is a front perspective view of shoe upper component in accordance with our new design;

FIG. 2 is a front elevation view thereof;

FIG. 3 is a rear elevation view thereof;

FIG. 4 is a right side view thereof;

FIG. 5 is a left side view thereof;

FIG. 6 is a top plan view thereof; and,

FIG. 7 is a bottom plan view thereof.
